COIN CONTROLLED MULTIPLE CERTIFICATE AND PRINTING MEANS

Adolphe C. Peterson, Minneapolis, Minn.

Application October 30, 1943, Serial No. 508,297

12 Claims. (Cl. 194—1)

1

My invention relates to coin controlled certificate and printing means, in an improved form which has certain multiple features, wherefore it is called "Coin controlled multiple certificate and printing means."

The principal objects of my invention are to provide an improved form of means certifying and printing or impressing upon documents or envelopes, which means shall be simple in construction, reliable in operation, certain in its mechanical operation and control, and more especially which shall have certain advantages not available in known devices or my devices of this character. An object is to provide in such devices a control means associated with electric driving means in order that such means shall have an advantage of simplicity and ease in manual operation for a user, so that the minimum of manual and mental exertion is required for such use. An object is to provide especially in such certifying means a simplicity in the inscription means while providing for variety or multiplication of the types of certificates which may be printed or inscribed under the control of a coin receiving means for a user. It is an object to provide an improved form of actuation for such means. It is an object also to provide a means of this type which shall provide, under the coin control, a larger number of numeral imprinting elements such that amounts varying from small to larger sums may be inscribed with greater facility by a user in one use, rather than in several uses of such a means or use of several such means or machines.

The principal devices and combinations of devices comprising my invention are as hereinafter described and as defined in the claims. In the accompanying drawings which illustrate my invention, like characters refer to like parts throughout the several views.

Referring to the drawings:

Figure 1 is a view chiefly in plan, with the enclosing casing in horizontal section, and some of the coin receiving means in horizontal section, the operating elements being all shown exposed by the sectioning of the casing.

Figure 2 is a view chiefly in vertical section on the lines 2—2 of Figures 1, 3, 4, 9, some means being shown in full side elevation, chiefly one numeral printing arm and associated elements.

Figure 3 is a detail sectional view on the line 3—3 of Figures 1, 2, looking rightwardly from that line in the figures.

Figure 4 is a detail sectional view on the lines 4—4 of Figures 1 and 2, looking leftwardly from

2

that line in the figures, this line being the same line as the line 3—3 named in connection with Fig. 3.

Figure 5 is a detail transverse sectional view on a vertical plane on the line 5—5 of Fig. 2, this view being enlarged to approximately twice the scale of the other figures, and is a section of one of the numeral holders.

Figure 6 is a detail in cross section on the line 6—6 of Fig. 1, on a vertical plane, through an electric contact means.

Figure 7 is a detail vertical sectional view on the line 7—7 of Figure 1, through one of the coin operated levers of the coin receiving means. (Sections through the other similar levers would be substantially similar except that a lesser number of shafts would be included, so such additional sections are not shown.)

Figure 8 is a detail vertical section on the line 8—8 of Figure 1, to show a section through one of the throw-back or restoring cams; a section through the other would be substantially similar.

Figure 9 is a plan view of the device as enclosed in its enclosing casing to show the relative placing of exposed elements, this view being on a much reduced scale.

Figure 10 is a view of the underside of the several inscription means, this view showing the inscriptions and numerals as they would print.

Figure 11 is a diagrammatic sketch of a form of electric circuit which would be used with my device.

Referring to the drawings, 1 is a base and 2 an enclosing casing which encloses the mechanical and electric component elements, and 3 is a shelf or small table upon which a user places his document or envelope for impression of a stamp certificate such as he desires and will determine by selection according to his coin insertions in 40 coin slots 4, 5, 6, and 7, 8, as shown exposed in Figure 9, and one of which is shown in section in Fig. 7, and all in horizontal section in Fig. 1.

The casing 2 has a projecting part 9 which projects somewhat over the shelf 3 or table, its lower panel 10 being spaced a small distance above the table 3, say one-quarter inch to one-half inch. The panel 10 of this part 9 has formed on its upper side and within part 9, a guide-well 11 which is merely a vertically projecting short wall around an aperture 12 in panel 10. This guide-well forms a guide in the downward descent for impression or inscription of the inscription means and does not enclose the impression means so tightly that this means may not have the

necessary freedom of movement to perform its downward descent for imprinting.

Within the guide-well 11 there are located one main inscription carrier 13 and five numeral element carriers, each of the latter denoted 14. The numeral element carriers 14 are each in horizontal section box-shaped and each has movable slightly vertically within it a numeral printer 15, the latter being preferably formed of ink absorbing and carrying porous metal of a type which has recently been devised for such purpose, the carrying of ink. Each of the numeral printers 15 on its lower face has a numeral some of which may be similar in character and others different, as hereafter described.

Each numeral element carrier 14 at its upper end is pivotally hung on the adjacent end of an associated numeral lever or actuator 16, there being one of the latter for each carrier 14. The numeral printer 15 at its upper end has a transverse projecting part 17 to limit downward movement relatively and has above it in the carrier a leaf spring 18 to yieldably press it downwardly relatively, the leaf spring being at an opposite end fixed to the underside of the associated lever 16.

The main inscription carrier 13 is horizontally of an elongated U-shaped form so as to enclose on three sides the group of numeral carriers 14. The main inscription carrier 13 is horizontally somewhat box-shaped to carry within it a porous metal main inscription printer 19, the latter having an inscription on its lower face, and having on its upper end arms 20 to limit downward movement relatively to the carrier 13. Coil springs 21 are mounted under compression between the printer 19 and the upper portion of carrier 13 to yieldably press the printer 19 relatively downwardly. The carrier 13 at its opposite ends has on its upper side a pair of bearing brackets 22 formed therewith, whereby the carrier 13 is pivotally mounted on the ends of the two carrier levers or arms 23 and 24. The carrier is pivoted on the axles 25, 26, but need not have but a very slight pivoting action. The carrier 13 and the carriers 14 are independently movable except as the control hereafter described, determines that movement, and each carrier 14 is independent of its neighbors 14.

The numeral levers or actuators 16 in inactive normal position extend parallel and adjacent each other rearwardly and the pair of carrier levers 23 and 24 likewise extend rearwardly parallel to each other, one on one side of the group of levers 16 and the other on the opposite side of that group 16. All of these levers 16 and 23 and 24 are at their extreme rear ends independently pivotally mounted on a fixed axle 27 as a bearing, the latter being in turned fixed stationary on the fixture standards 28, and thereby on base 1. The levers 23 and 24 have each a coil spring 29 compressed beneath it, between it and base 1 to yieldably hold it in its normal elevated position, as shown. The levers 16 are each held yieldably in its normal elevated position as shown by a small leaf spring designated 30, there being one for each lever 16, placed under its rearward end, as shown in Fig. 2, as to one only.

The levers 16 each have the form shown in Figure 2, as to one, and each is slotted mid-way of its length as shown in Fig. 1, and has slidably horizontally in that slot, designated 31, as to each, an intermediary element designated 32, as to each, the intermediary element 32 having tongues 33 which slide in counter-part grooves in

the sides of the lever 16 associated internally of the slot, for guidance of the movement of the intermediary element relative to the associated lever 16. The intermediary element 32 has on its upper edge a projected cam face 34 which is an intermediary cam, and on its lower edge has a projecting lug or member 35 which serves two purposes, one to hold the adjacent end of an associated coil spring 36, one for each lever 16, this spring 36 serving to pull intermediary element 32 leftwardly in Fig. 2, and secondly serves to contact the circuit closing means as hereafter described. The intermediary element 32 has also at its extreme rightward end in Fig. 2, a sidewaysly projecting pin or lug 37 which at the rightward end of the movement of the intermediary element 32 is engaged by the hook 38 and thereby the intermediary element 32 is normally held rightwardly in the position shown in Fig. 2. There is one hook 38 for each intermediary element 32 and thus also for each printer lever 16. Each hook 38 is normally yieldably pressed upwardly by the coil spring 39, of which there is one for each hook 38, and each hook 38 has the inclined approach end 40 for the purpose hereafter described. Each intermediary element 32 has also projecting further upwardly from its upper edge and rightwardly from the cam face 34, a lug or pin 41, which serves for contact with a restoring means for a restoring movement as hereafter described. The intermediary elements 32 may otherwise for distinction in the claims be called "intermediary selection elements."

There is mounted rightwardly of the fixed axle 27, about one-third of the distance or length of the levers, an actuator shaft 42 which is the main actuating element of the device and its main control means for the control of the cyclic movements in operation. The actuator shaft 42 is rotatably mounted in the pair of fixed bearing standards 43 and also one 44 and has as its principal operative means one integral cam 45 which extends across the upper side of all of the levers 16 and levers 23 and 24 also so as to have effect at a like time in the cyclic movement on any of the levers 16 or 23 and 24, according to the determination, as hereafter described. The actuator shaft 42 has also formed integrally with it two cams 46 and 47 which are similarly placed radially so as to perform in unison, but so as to perform their function at a different period in the cycle of movement, that is after the performance of the cam 45 of its function, as hereafter described. The actuator shaft 42 has fixed on it to revolve with it a cylindrical insulator 48 and a broken circumferential contact 49. The actuator shaft 42 has also fixed on it or formed integrally with it a rather large diameter worm wheel 50 and the latter is in constant engagement with for driving by a worm pinion 51. The latter is fixed on the armature shaft 52 of the electric motor 53, there being thus a large reduction between the motor 53 and the shaft 42.

The one cam 45 is adapted to engage the levers when it has one-half completed its single cycle of rotation or movement in the impression operation, and in this cycle it will always engage the pair of levers 23 and 24 so as to downwardly depress the main inscription carrier 13, but will not engage any of the levers 16 directly but only such of the levers 16 as are selected for this engagement by release of the intermediary element 32 associated with it by a coin reception, as hereafter described. A lever 16 will be engaged by

this cam 45 in its cycle of movement, when its intermediary element 32 occupies a position leftwardly of the position, as shown in Fig. 2, that is so that the intermediary cam face 34 is directly underneath the axis of actuator shaft 42 and by such engagement the lever 16 will be depressed a sufficient distance for the impression movement while any of the levers 16 which do not have their intermediary elements 32 so released, will not be affected.

The pair of cams 46 and 47 will in unison contact the adjacent side of the pair of levers 54, 55, so that by this contact the levers, fulcrumed at 56 on fixed standards, are thrust rightwardly in Fig. 2, and carry with them the cross bar 57 which is fixed on the lower ends of levers 54, 55 by its ends. This rightward movement of the cross bar 57, which with its levers 54, 55 is a restoring means, will engage the upwardly projecting lugs 41 of any intermediary elements which had been released, and by this contact will push such lugs 41 and with them the intermediary elements 32 rightwardly in Fig. 2, so that thereby the intermediary elements 32 are restored to their normal rightward or inactive position, as is shown in Fig. 2, thereby these levers 54, 55 and cross bar 57 and cams 46, 47 perform the function of restoring the selection means to the normal positions for renewed coin insertions and selections. Members 54, 55, 57 are loosely hung so that they do not interfere with the release and leftward movement of the intermediary elements.

The actuator shaft 42 at one end has fixed thereon or integrally formed with it, a crank 58 which has secured on it pivotally one end of the coil spring 59, the opposite end thereof being fixed on the fixed standard 60, the spring 59 serving the function of yieldably holding the actuator shaft 42 in the position shown, which is the initial or inactive position, and to induce the actuator shaft 42 to come finally to this position at the end of its cycle of rotation.

The lugs 35 of any of intermediary elements 32 will in the leftward movement, viewed in Fig. 2, contact the cross member 61 on the upper end of the circuit closer lever 62, which is fulcrumed at 63, and yieldably placed by spring 64, and by this contact will close the contact between it and the contact spring 65, to close the operating circuit, when a supplemental hand contact or closer 66 is manually pressed, as hereafter described.

Each hook 38 is fixed on one end of an independently associated shaft, 67, or 68, or 69, or 70, or 71. There are thus five of these shafts, and the number may be more or less according to the number of levers 16. Some of these shafts are hollow, and three of the shafts are coaxial on one side of the levers and the others are coaxial on the other side, the axes of all extending coincidently and transversely, underneath the levers. Each of these shafts at the end opposite to that on which the hook 38 is fixed, has fixed on it a coin actuated lever 72, 73, 74, 75, 76, each of which is located in a coin passage associated and which is part of one of the associated coin slots 4, 5, 6, 7, or 8. The coin passages deliver either into the coin box 77 or the coin box 78. The coin actuated levers are held in their upward positions yieldably, by the springs associated with the hooks 38. These coin reception elements are shown only in the most elemental form and as necessary to show a means for coin reception, it being contemplated that the coin reception means may be of any

known type such as may be adapted for reception of coins and to preclude tampering by a user.

The contact 49 of shaft 42 is adapted to make contact with a contact spring 79 immediately after the actuator shaft 42 commences its cycle of rotation, which is a single complete rotation, and this contact will then be maintained until a moment immediately prior to the return to the normal position of shaft 42, that shown in the figures.

Each numeral printer 15 will have on its lower face such numeral as it may be determined is most suitable for the particular usage of the device whether for postage certification or for money order certification or other use. When used for money certification more than one numeral may be used on at least some of the numeral printers, say for instance the number 10 or the number 25. When used for postage certification, preferably the numeral printers will have single numerals on their printing face, and preferably at least three will have the numeral 1, while at least one of the remaining two will have the numeral 5. It may be assumed for description that four of the numeral printers have the numeral 1 and one has the numeral 5. Preferably each will also have certain other insignia such as small identifying inscriptions.

For use of the device, it may be placed in any store, as a drug store, any post office lobby, or any hotel lobby or theatre lobby, or any other place frequented by the public. The device will be served with electricity either from main wires or a battery, depending on construction. The electric motor will be capable of operation in one direction only. The user will place the document or envelope upon which he desires a certification of postage upon the table 3, and he then will place coins in the coin slots according to the amount of postage certification he desires. Assume that he desires a certification of two cents postage. He then places one cent in one cent slot and another cent in another one cent slot. Assume he desires a three cent postage certification instead, he places an additional cent in still another one cent slot. Assume he desires a four cent postage certification, he would deposit still another cent in still another of the one cent slots of which there are four, as assumed. But suppose he desires a six cent certification he would instead deposit one five cent coin in the five cent slot and one one cent coin in one of the one cent coin slots. Or suppose he desires a nine cent certification, he would deposit one five cent coin in the five cent slot and one one cent coin in each of the other, that is the one cent coin slots. In any case, whatever certification he desires he would not touch the push button 66 until he has completed his deposit of coins to the amount of certification he desires, this amount in total, however, not exceeding the added total of the numerals on the numeral printers 15, which as assumed would be 5 plus one, plus one, plus one, plus one, or nine.

Having completed the coin deposit, not more than one coin being placed in any one slot, the user then touches the push button 66 and holds this closed for a second or two or just until the motor has commenced turning its armature shaft and thereby has turned the main actuator shaft 42 slightly so that the contact 49 has contacted contact spring 79 and closed this parallel circuit, whereby the circuit through the electric motor is maintained until just prior to the completion of the cycle of shaft 42. The shaft 42 has only one complete revolution to perform one impression or

imprinting operation. Having started this operation, which cannot be started until at least one coin has been deposited the operation is automatic until completed. By deposit of one coin or the full complement of coins, namely five, as shown, there will have been released one or more of the intermediary elements 32, by the swinging of one or more of the hooks 38 downwardly as the coin deposited moves past the associated coin lever, since each coin lever is fixed on the same shaft as one hook 38. The release of any one of the intermediary elements 32 causes a contact with the cross bar 61 whereby this with its attached contact is swung to position of contact and so held until the cycle of operation has commenced by touching of push-button 66 and closing of contacts 49-79.

The operation having been commenced the shaft 42 continues its rotation until completion of one rotation and successively the functioning is then as follows: first, approximately when the rotation is one-half complete, the cam 45 contacts the pair of levers 23-24 associated with the main inscription carrier 13, and at the same time contacts also such of the intermediary elements 32 as have been released by coin deposits, and such simultaneous contact will cause depression for the imprinting operation of the main inscription carrier 13 with its printer, and also each of the numeral printer levers 16 whose associated intermediary elements 32 have been released whether that be one or more or all five, the imprinting being thus accomplished; second, the depressed levers are released to return upwardly as the cam passes; third, the pair of cams 46 and 47, contact the pair of levers 54-55 thereby thrusting cross bar 57 rightwardly as shown in Figs. 1 and 2, whereby the released intermediary elements 32 are returned by contact with the lugs 41 thereof, and all released intermediary elements 32 are restored to their normal positions or inactive positions as shown; fourth, immediately prior to completion of the cycle, the contact 49 breaks contact with contact 79; fifth the strong coil spring 59 exerts a continuing pull on the crank 58 of shaft 42 so as to continue rotation of shaft 42 the slight amount necessary to complete the rotation, and so that the shaft 42 will then stand in the position shown in which position, the crank is in line with the coil spring attached and the axis of shaft 42; sixth, the shaft 42 comes to rest at this normal position as shown. The worm pinion and worm wheel of the motor drive should be so formed as to permit this continuing movement by the spring action, and in lieu of the worm wheel and pinion any spur gear reduction means may be used if that better facilitates this action in any type of construction for production.

The cycle having been thus effected, the main inscription means and the numeral printers have then imprinted with ink on the document or envelope on table 3, the desired inscription or certification, that including something of the type shown in Figure 10 and as many of the numerals as have been selected by coin deposits. The operation having been completed, the device cannot be used for a new certification until a user has again deposited a coin or series of coins in the device.

The battery M may supply electric current or any current supply by which the motor may be driven in one direction only may be used. Any number of numeral printers may be used. The device may be used for money order certification

for small money orders such as amounts under a dollar or several dollars, the inscriptions being made accordingly and according to the use for which intended.

While I have shown particular devices and combinations of devices in the illustration of my invention, I contemplate that other detailed devices and combinations of devices may be used in the realization of my device without departing from the spirit and contemplation thereof.

What I claim is:

1. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position, and a motor means to move said main control element through its cycle to effect the said impression movement through said intermediary element.

2. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position, an electric motor means for driving said main control element through said cycle of movement and a current source and circuit control means in association with said electric motor means and said current source to effect operation of said main control element through its said given cycle.

3. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position, an electric motor means for driving said main control element through said cycle of movement and a current source and circuit control means in association with said electric motor means and said current source to effect operation of said main control element through its said given cycle.

trol element through said cycle of movement, a current source, a circuit control means in association with said electric motor means and current source said circuit control means including a circuit completer normally open but interconnected with said intermediary element and coin reception means to be closed when said intermediary element is permitted movement to its said second position.

4. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position, an electric motor means for driving said main control element through said cycle of movement, a current source, a circuit control means in association with said electric motor means and current source said circuit control means including a main circuit completer normally open but interconnected with said intermediary element and coin reception means to be closed when said intermediary element is permitted movement to its said second position, and including in combination a supplementary circuit completer moving with said main control element and supplementary contact means in association therewith to effect a continued circuit of said current source and said motor means during all of the cycle of said main control element except a portion related with the inactive position of said main control element.

5. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position, an electric motor means for driving said main control element through said cycle of movement, a current source, a circuit control means in association with said electric motor means and current source said circuit control means including a main circuit completer normally open but interconnected with said intermediary element and coin reception means to be closed when said intermediary element is permitted movement to its said second position, and including in combination a supplementary circuit completer moving with said main control element and supplemen-

tary contact means in association therewith to effect a continued circuit of said current source and said electric motor means during all of the cycle of said main control element except a portion related with the inactive position of said main control element, and a manual circuit closer included in the circuit completer to break said circuit therethrough except when manually closed.

6. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position, an electric motor means for driving said main control element through said cycle of movement and a current source and circuit control means in association with said electric motor means and said circuit control to effect operation of said main control element through its said given cycle, and in combination a yieldable tension means interactuation with said main control element to yieldably induce said main control element to move to and rest in its normal position in the condition for new cyclic actuation.

7. In a coin controlled impression means, a plural number of impression elements each independently movable for impressing, an intermediary selection element for each impression element movable from a first position to a second position to place the associated impression element in condition for impression movement, a main control element adapted to be actuated through a given cycle to effect impression movement of selected impression elements through said intermediary selection elements as have been moved to said second positions and to effect restoration of said intermediary selection elements to their first positions in sequence, means to normally retain said intermediary selection elements in said first positions and to effect movement of selected intermediary selection elements to said second positions, a coin reception means interconnected with said last named means to effect therethrough the placing of selected intermediary selection elements in their second positions, and in combination a motor means for driving said main control element through said cycle of movement and a circuit control means and current source in association therethrough including a main circuit completer normally open but interconnected with said intermediary selection elements and said coin reception means to be closed when any one of said intermediary selection elements is permitted movement to its second position.

8. In a coin controlled impression means, a plural number of impression elements each independently movable for impressing, an intermediary selection element for each impression element movable from a first position to a second position to place the associated impression ele-

ment in condition for impression movement, a main control element adapted to be actuated through a given cycle to effect impression movement of selected impression elements through said intermediary selection elements as have been moved to said second positions and to effect restoration of said intermediary selection elements to their first positions in sequence, means to normally retain said intermediary selection elements in said first positions and to effect movement of selected intermediary selection elements to said second positions, a coin reception means interconnected with said last named means to effect therethrough the placing of selected intermediary selection elements in their second positions.

9. In a coin controlled impression means, a plural number of impression elements each independently movable for impressing, an intermediary selection element for each impression element movable from a first position to a second position to place the associated impression element in condition for impression movement, a main control element adapted to be actuated through a given cycle to effect impression movement of selected impression elements through said intermediary selection elements as have been moved to said second positions and to effect restoration of said intermediary selection elements to their first positions in sequence, means to normally retain said intermediary selection elements in said first positions and to effect movement of selected intermediary selection elements to said second positions, a coin reception means interconnected with said last named means to effect therethrough the placing of selected intermediary selection elements in their second positions, an electric motor means for driving said main control element through said cycle of movement and a current source and circuit control means in association with said electric motor means and said current source to effect operation of said main control element through its said given cycle.

10. In a coin controlled impression means, a plural number of impression elements each independently movable for impressing, an intermediary selection element for each impression element movable from a first position to a second position to place the associated impression element in condition for impression movement, a main control element adapted to be actuated through a given cycle to effect impression movement of selected impression elements through said intermediary selection elements as have been moved to said second positions and to effect restoration of said intermediary selection elements to their first positions in sequence, means to normally retain said intermediary selection elements in said first positions and to effect movement of

selected intermediary selection elements to said second positions, a coin reception means interconnected with said last named means to effect therethrough the placing of selected intermediary selection elements in their second positions, the said last named means having a plural number of elements each associated with one of said intermediary selection elements and to be actuated by reception of a coin in association with it.

11. In a coin controlled impression means, a plural number of impression elements each independently movable for impressing, an intermediary selection element for each impression element movable from a first position to a second position to place the association impression element in condition for impression movement, a main control element adapted to be actuated through a given cycle to effect impression movement of selected impression elements through said intermediary selection elements as have been moved to said second positions and to effect restoration of said intermediary selection elements to their first positions in sequence, means to normally retain said intermediary selection elements in said first positions and to effect movement of selected intermediary selection elements to said second positions, a coin reception means interconnected with said last named means to effect therethrough the placing of selected intermediary selection elements in their second positions, the said last named means having a plural number of elements each associated with one of said intermediary selection elements to be actuated by reception of a coin in association with it, and an electric motor means for driving said main control element through said cycle of movement and a current source and circuit control means in association with said electric motor means and said current source to effect operation of said main control element through its said given cycle.

12. In a coin controlled impression means, an impression element movable for impressing, an intermediary element movable from a first position to a second position to place said impression element in condition for impression movement, a main control element adapted to be actuated through a given cycle to effect impression movement of the impression element through said intermediary element when said intermediary element is in said second position and to effect restoration of said intermediary element to its first position in sequence, means to normally retain said intermediary element in said first position and to effect movement of said intermediary element to said second position, a coin reception means interconnected with said last named means to effect therethrough the placing of said intermediary element in said second position.

ADOLPHE C. PETERSON.
